SWITCH ACTUATING MECHANISM
FOR A TOY BOAT
Neal Hageal, 1105 Fair Oaks Place, New Kensington, Pa.
Filed July 9, 1963, Ser. No. 293,808
1 Claim. (Cl. 200—172)

This invention relates to boats and, in particular, to an on-and-off switch for controlling the operation of a battery-powered motor in a toy boat.

The object of my invention is to provide a simple, inexpensive switch which may be easily operated manually both when the boat is lying at rest and when it is in motion.

According to the invention, I make use of the dummy steering wheel and post, usually provided in toy boats, by a special mounting thereof, to constitute it a switch in the circuit including the battery and the motor.

A preferred embodiment is shown in the accompanying drawings in which

FIG. 1 is a partial plan view;

FIG. 2 is a partial section along the plane of line II—II of FIG. 1 with parts in elevation;

FIG. 3 is a section along the plane of line III—III of FIG. 2; and

FIG. 4 is a partial section along the plane of line IV—IV of FIG. 2.

Referring now in detail to the drawings, a boat hull 10 has a cockpit 11 and an instrument panel 12 extending forwardly thereof. A steering wheel 13 is mounted on a post 14. The lower end of the post, which comprises a shaft 20, is journaled in a bearing 15 upstanding from the bottom of the boat below panel 12, which permits tilting movement of the post in a vertical plane. The upper end of the post projects upwardly of the panel 12 through a slot therein.

2

A contact member 16 is mounted on an arm 17 at the lower end of post 14 so that, on tilting movement of the latter, member 16 will engage and bridge spaced fixed contact members 18, one on each side thereof. By making suitable connections to members 17 in an obvious manner, the switch afforded by post 14 and contact members 16 and 18 may be caused to control a battery-powered motor (not shown) suitably mounted in or on the boat. Post 14 is rotatably held in bearing 15 by a notched bracket 19 integral with panel 12. As is conventional, the boat hull is molded in one piece and the panel and deck in another, the two pieces being joined in any suitable manner.

It will be evident that tilting of the steering post 14 to effect opening or closing of the switch may be readily effected whether the boat is moving or at rest.

I claim:

In a toy boat, a hull and an instrument panel fitted therewith, the combination therewith of a switch actuating mechanism comprising a bearing upstanding in said hull, a shaft journaled horizontally in said bearing abeam of the hull, a bracket depending from said panel holding said shaft in said bearing, said panel having a slot therein and a post carried by said shaft and extending upwardly through said slot.
